UNITED STATES PATENT OFFICE.

STEPHAN PRUZENSKI, OF BUFFALO, NEW YORK.

RAILWAY-CAR BRAKE.

Application filed March 5, 1925. Serial No. 13,194.

This invention relates to certain new and useful improvements in railway car brakes and particularly to the type embodying a removable braking face plate that is interlockingly associated with a brake head or body and has for one of its objects to provide a novel form of locking connection between the head and face plate.

A further object of the invention is to provide a car brake wherein a face plate or shoe is removably connected to a braking head with the connecting device between the shoe and head being in the form of a tensioned pin or key having the operating end thereof confined in a cutaway portion in the head.

A still further object of the invention is to provide a novel mounting for the tensioned pin that establishes the interlocking connection between the brake head and shoe wherein a tubular housing threaded into the brake head encloses the tensioned key.

With the above and other objects in view that will become apparent as the nature of the invention is better understood, the same consists of the novel form, combination and arrangement of parts hereinafter more fully described, shown in the accompanying drawing and claimed.

In the drawing, wherein like reference characters designate corresponding parts throughout the several views:—

Figure 1 is a side elevational view of a railway car brake constructed in accordance with the present invention, a portion of a car wheel being illustrated by dotted lines.

Figure 2 is a top plan view of the brake showing the supporting rods therefor.

Figure 3 is a fragmentary sectional view showing the interlocking connection between the brake head and removable brake face or shoe with the tensioned pin holding the parts in engagement.

Figure 4 is a detail sectional view taken on line IV—IV of Fig. 3, showing the angle extension end of the locking pin or key to facilitate operation thereof,

Figure 5 is a perspective view of the tensioned locking key and illustrating by dotted lines, one end thereof bent to form a gripping handle.

Referring more in detail to the accompanying drawing, there is illustrated a railway brake wherein the brake head 1 is supported by the cross bar 2 that may be suitably braced by the angle rod 3.

A braking face or shoe 4 is detachably connected to the inner face of the brake head 1 and the connection between the brake head and shoe includes the formation of a block 5 upon the inner face of the brake head 1 intermediate the ends thereof as clearly illustrated in Figs. 1 and 3 and further provided with a socket 6 extending transversely of said block for the removable reception of the lug projection 7 upon the brake shoe 4. The central block projection 5 upon the brake head 1 forms side openings 8 in the brake device between the central block 5 and the opposite contacting ends of the head and brake shoe as clearly shown in Fig. 1.

To retain the brake shoe in position upon the brake head, a tensioned locking pin or key is associated with the head block 5 and the brake shoe lug 7, one side of the block 5 that opens into one of the pockets 8 having a threaded opening therein that receives the externally threaded sleeve or housing 9 that is closed at its outer end by the centrally apertured boss 10 while the bottom wall of the opening that receives the housing 9 is provided with an opening that communicates with the socket 6. A key 11 of the type illustrated in detail in Fig. 5 and having diametrically opposite lug projections 12 adjacent the inner end thereof is slidably mounted in the housing 9 with the upper end thereof slidably projecting through the apertured boss 10 and bent at right angles thereto as at 13 to form a handle grip, the inner locking end of the key 11 passing through the opening in the inner end of the housing 9 and through the opening 14 in the brake shoe lug 7 with the terminal end thereof received in the depression 15 formed in the block 5 at the opposite side of the brake shoe lug 7. A coil spring 16 surrounds the locking key 11 between the boss 10 and the opposite lugs 12 for forcing the operative end of the locking key in a direction to project the same through the opening in the brake shoe lug 7 as shown in Fig. 3.

It will be noted that the handle grip 13 of the locking key is confined within one of the pockets 8 so that protection is provided therefor to prevent accidental displacement thereof. The threaded sleeve 9 provides a safe housing for the locking key 11 and is removable from the block 5 to permit free access to the locking key and spring for

purposes of repair or the like. The engaging ends of the brake head and shoe have interlocking faces and the locking key connection between the ends of the head and shoe provide a rigid mounting for the brake shoe.

While there is herein shown and described the preferred embodiment of the present invention, it is nevertheless to be understood that minor changes may be made therein without departing from the spirit and scope of the invention as claimed.

What is claimed is:—

1. In a wheel brake, a head, a shoe detachably connected to the head and said connection including interengaging projections on the head and shoe, a housing carried by the upper of the projections of said head, a tensioned key in the housing having a lower operating head extending through the

interengaging projections; said key also having a right angular upper end for manipulating said key, and said housing and key being removable from said head projection.

2. In a wheel brake, a head, a shoe detachably connected to the head and said connection including interengaging projections on the head and shoe, a removable housing threaded into the uppermost of the projections of said head, a key slidable in the housing and having opposite lugs remote from the operative end of the key extending through the projections, and a coil spring surrounding the key between the lugs and outer end of the housing, said key having an outwardly directed angular manipulating handle at its upper end above said housing.

In testimony whereof I affix my signature.

STEPHAN PRUZENSKI.
